United States Patent Office

Des. 228,967
Patented Oct. 30, 1973

228,967

FOOT MASSAGER OR SIMILAR ARTICLE

Joseph A. Holladay, 1304 Amity Ave.,
Nampa, Idaho 83651

Filed July 28, 1971, Ser. No. 167,067

Term of patent 14 years

Int. Cl. D24—99

U.S. Cl. D83—1 S

FIG. 1

FIG. 2

FIG. 1 is a right front perspective view of the foot massager or similar article embodying my new design with the roller carrier member in exploded view.

FIG. 2 is a bottom right rear perspective view with the roller carrier member in exploded view.

I claim:

The ornamental design for a foot massager or similar article, substantially as shown and described.
